UNITED STATES PATENT OFFICE.

POVL T. LINDHARD, OF BROOKLYN, NEW YORK, ASSIGNOR TO F. L. SMIDTH & CO., OF NEW YORK, N. Y., A CORPORATION OF NEW JERSEY.

BALL-GRINDING MILL.

Application filed September 20, 1924. Serial No. 738,767.

To all whom it may concern:

Be it known that I, POVL T. LINDHARD, a citizen of the United States, residing in the borough of Brooklyn, of the city of New York, in the State of New York, have invented certain new and useful Improvements in Ball-Grinding Mills, of which the following is a specification, reference being had to the accompanying drawings, forming a part hereof.

This invention relates to ball grinding mills of the general type of those shown in Letters Patent of the United States No. 694,874, March 11, 1902, No. 737,750, September 1, 1903, and No. 740,879, October 6, 1903, which have screening devices combined with the grinding drum and are arranged for continuous feed of the material operated upon and continuous discharge of the screened material, while the tailings are returned from the screens to the drum for regrinding. In the operation of such machines the screens are subjected to severe wear and it is necessary to remove and replace them from time to time. Heretofore the screens have been so mounted as to require considerable time in their removal and replacement. One object of the invention is to improve the construction so as to require less time and labor in the removal and replacement of the screens. Heretofore, also, the provision for the return of the tailings from the screens to the grinding drum has been such that the tailings from one screen must pass the discharge end of another screen before reaching the grinding drum so that the free discharge of the tailings from some of the screens is interfered with by the passage through the common conductor of the tailings from other screens and it is therefore another object of the invention to overcome this difficulty. Still another object of the invention has been to construct the mill in such manner that the screens can be reversed with respect to the grinding drum so that the drum can be rotated in one direction or in the other as may be most convenient. Other features of improvement will be referred to more particularly herein-after. In the drawings, in which is illustrated a grinding mill which embodies the several features of the present invention—

Figure 1 is a view of the improved machine in longitudinal, sectional elevation.

Figure 2, as to the right hand half, is a view in elevation, as seen from the right hand in Figure 1, with the supporting shaft and the dust casing in section and, as to the left hand half, an elevation as seen from the left hand in Figure 1, also with the casing and the shaft in section.

Figure 3 is a view in longitudinal section showing one of the conical screens and the means at one end for supporting it in position with respect to the grinding drum, a portion of which is also shown, the scale of this figure being larger than that of Figures 1 and 2.

Figure 4 is a view partly in elevation of the parts shown in Figure 3, as seen from the left hand, and partly in section on the plane indicated by the broken line 4—4 of Figure 3.

Figures 5 and 6 are detail views in sectional elevation and section, on different planes which are radial with respect to the axis of the machine, showing details of construction of the devices by which each conical screen is supported in its smaller end.

Figures 7 and 8 are detail views of some of the devices shown in Figures 5 and 6, in elevation, looking toward the axis of the mill.

Figure 9 is a view in section on a plane at right angles to the axis of the mill, through the parts through which the tailings are returned from the three screens of one group to the grinding drum.

Figure 10 is a detail view in section of parts shown in Figure 3.

Figures 11, 12 and 13 are detail views in section on the planes indicated by the broken lines 11—11, 12—12 and 13—13 of Figures 2 and 9.

Figure 14 is a detail view in elevation of some of the parts shown in Figure 11 with the securing bolt in section.

In the improved mill illustrated in the drawings as an embodiment of the invention, the shaft *a* is mounted in suitable bearings *a'*, receives at one end the wheel *a*² through which the mill is driven and supports, through hubs *b* and *b'*, the end walls *b*², *b*³ and the circumferential wall *b*⁴ of the grinding drum, which is provided as usual with suitable liners. A dust casing *c* encloses the grinding drum, together with the screens and accessories hereinafter re-

ferred to, and is provided with a discharge opening, as at c' , through which the screened material received from the screens is discharged. At one end of the casing is a feed 5 hopper d which delivers material through the hub b into the grinding drum to be acted upon therein by the usual grinding bodies which are not shown. At the opposite end of the grinding drum, near its periphery, is an annular grating e through which the material which has been acted upon by the grinding bodies is discharged into an annular space e' , within the end wall b^a of the drum and thence, as will be 10 described, into the smaller ends of the conical screens f which are mounted in a circumferential series about the periphery of the grinding drum.

The annular flange g has secured thereto 20 by bolts g' a circumferential series of trough-like castings or saddle pieces h which are also bolted together, end to end, as at h' , there being one such trough-like casting for each screen. Each casting 25 or saddle-piece is formed as shown with a central deflecting surface by which the material received from the drum is deflected into the screen from either side according to the direction in which the mill is 30 rotated. Each casting, which is symmetrical with respect to the axis of the corresponding conical screen, has a cap piece i which is held to the casting h by a bolt i' , the head of which fits into a recess h^2 in the casting 35 h . The cap piece is provided with handles i^2 to facilitate its removal. The casting and the cap piece are formed to receive a ring f' which is fitted upon the smaller end of the screen f , the cap piece being shouldered at i^3 40 so that when it is in position there can be substantially no longitudinal movement of the ring f' and the screen f toward the casting, but when the cap piece is removed, the ring f' , with the screen f , can be moved 45 further into the casting, in the space indicated at h^3 , for a purpose to be referred to hereinafter.

In the operation of the mill the material 50 which passes through the grating e into the annular space e' , passes thence through openings g^2 in the flange piece g and into the space h^4 within the casting h and thence, through an opening h^5 in the casting, continued also into the cap piece, into the open 55 end of the screen f . It will be noted that the rib or flange h^6 of the casting h serves to prevent the material in the conical screen f from working back into the grinding drum as each screen passes through the upper arc 60 of its travel.

The larger end of each conical screen f is received in a ring f^2 which has a coned seat at f^3 in a casting h , the ring f^2 being held in place by bolts f^4 , which insure the proper setting of the ring f^2 in the casting h , 65

Each screen can therefore be removed by taking out the two bolts f^4 at the larger end and the single bolt i' at the smaller end, removing the cap piece i , and then moving the screen endwise so as to free the ring f^2 70 from its seat in the casting h . The correct placing of the cap piece i with respect to the casting h is assured by dowel pins, the position of which is indicated at h^7 in Figure 8. 75

Each hollow casting h is formed with a lug h' which receives in one direction one of the bolts f^4 above mentioned and at right angles thereto a bolt h^2 by which it is secured in place. 80

It will be observed that each hollow casting h is symmetrical with respect to its major axis so that it can be turned about the axis of the screen f from the position shown at the left hand in Figure 2 to the opposite position. The purpose is to permit the parts to be assembled for rotation of the mill either in a right hand direction or in a left hand direction as the convenience of the user may dictate, without requiring the provision of special castings. The parts through which the tailings are conducted from each hollow casting h back to the inside of the grinding drum b^2 , b^3 , b^4 are also formed so that they can be reversed in position according to the direction of rotation of the mill without requiring the provision of special castings. Again, the parts are so constructed and arranged that the tailings from a group of three screens f are returned to the grinding drum through a common collecting tube or conduit which is made up of four sections, the first two of which are identical and reversible, six such sections being required for a mill having nine screens, as in the construction illustrated, while the third and fourth are also reversible, three of each being required in a mill having nine screens. Furthermore all parts of the collecting and conducting means are located within the circle of the screens so that the destructive effect of centrifugal action is reduced as compared with a construction in which the collecting tubes are outside of the circle of the screens, and so that the return of the tailings from each screen to the grinding drum is interfered with to a much less extent than would be the case if the tailings were discharged into a collecting tube outside of the circle of the screens. By the improved arrangement, also, the aggregate weight of the parts is much reduced. 100

The collecting and return conduit for each 105 group of three screens comprises four parts l , m , n and o . The parts l and m , as above stated, are identical, each comprising a collecting tube l' , m' , flanged at its ends and a connecting tube l^2 , m^2 , which is flanged at 110 one end for connection to the flanged end

115

of the hollow casting k and serves to deliver the tailings from such casting into the connecting tube section l' or m' . The part n comprises a collecting tube section n' , flanged at its ends, and a connecting section n^2 flanged for connection to the third casting k of the group and serving to deliver the tailings from the corresponding screen to the collecting tube section n' . The section n also has a web bracket n^3 with a transverse plate n^4 , to which the corresponding end of the next collecting tube section l' is secured. The tube sections l' and m' are curved upon a common radius so as to direct the material toward the axis of the drum. The fourth section o , also reversible, is flanged at one end for connection to the tube section n' and at its other end is fitted into a radial opening b^5 in the hub b of the grinding drum, which opening is deflected, as shown in Figure 1, so as to deliver the tailings into the interior of the drum.

Each part k is secured by the bolt k^2 , above mentioned, to the connecting tube l^2 , m^2 or n^2 , between it and the axis of the drum, and each of the sections l , m , n is secured by a single bolt p to the annular angle piece b^6 which unites the adjacent end wall b^2 and the circumferential wall b^4 of the grinding drum, as shown particularly in Figure 11. As shown, the bolt p passes through an eccentric bushing p' in which its angular head p^2 is seated. The eccentric p' , rotatable by the application of a wrench applied to the head p^2 of the bolt, is seated in a bearing block p^3 which is secured by bolts p^4 to a bracket p^5 riveted to the end of the grinding drum. The other end of the bolt is received in a shouldered ring p^6 and receives a nut p^7 at the outside of the corresponding section of the collecting and conducting means. The eccentric p' performs no special function in the operation of the mill but serves a convenient purpose in assembling the several parts of the collecting and conducting tube as it permits adjustment of the parts to each other without requiring accurate machining of such parts.

The several details of improved construction above described may or may not be incorporated in the same mill although they have been designed for mutual coaction with a view to reduction in the cost of construction of the mill as a whole, the adaptation of the mill for rotation in one direction or the other as may suit the convenience of the user, facility in the removal and replacement of the screens, and increase in the efficiency of operation of the mill as a whole.

It will be understood that various changes can be made in details of construction and arrangement to suit the convenience of the manufacturer and the requirements of the user and that, except as pointed out in the claims, the invention is not limited to the

precise construction shown and described herein.

I claim as my invention:

1. In a grinding mill, the combination of a grinding drum, a series of tubular screens disposed about the periphery of the grinding drum and supported thereby to revolve therewith, means to deliver ground material from the drum to the screens at one end thereof, and means at the other end of the screens to return the tailings from the screens to the drum, such means including a common collecting tube for a group of screens, a connection from each screen of the group to the collecting tube and a connection from the collecting tube to the interior of the drum.

2. In a grinding mill, the combination of a grinding drum, a series of tubular screens disposed about the periphery of the grinding drum and supported thereby to revolve therewith, means to deliver ground material from the drum to the screens at one end thereof, and means at the other end of the screens to return the tailings from the screens to the drum, such means including a common collecting tube for a group of screens, a connection from each screen of the group to the collecting tube and a connection from the collecting tube to the interior of the drum, all of said collecting and connecting means being located within the circle of the screens.

3. In a grinding mill the combination of a grinding drum, a tubular screen supported by the grinding drum to revolve therewith, means including a hollow casting to support the screen at one end and receive the tailings therefrom, such casting being symmetrical about its longitudinal axis and reversible in direction, a collecting tube connected to said casting at one end and a connection from the collecting tube to the interior of the drum, the collecting tube being reversible in position to conform to the position of the hollow casting.

4. In a grinding mill the combination of a grinding drum, a series of screens disposed about the periphery of the grinding drum and supported thereby to revolve therewith, means including a hollow casting to support each screen at one end and receive the tailings therefrom, a common collecting tube for a group of screens, a connection from each screen of the group to the collecting tube, and a connection from the collecting tube to the interior of the grinding drum.

5. In a grinding mill the combination of a grinding drum, a series of screens disposed about the periphery of the grinding drum and supported thereby to revolve therewith, means including a hollow casting to support each screen at one end and receive the tailings therefrom, a collecting

tube comprising three sections secured together and each having a connection to the corresponding hollow casting, and a connection from the collecting tube to the 5 drum.

6. In a grinding mill the combination of a grinding drum, a tubular screen supported by the drum to revolve therewith, a hollow casting to support the screen at one 10 end and receive the tailings therefrom, a collecting tube section with a connection to the hollow casting, a connection from the collecting tube to the interior of the grinding drum, and adjustable means to secure 15 the collecting tube section to the grinding drum, such means comprising a bearing end bracket secured to the drum, an eccentric rotatably mounted in the bearing, and a bolt to secure said section to said eccentric.

20 7. In a grinding mill the combination of a grinding drum, a series of tubular screens disposed about the periphery of the grinding drum and supported thereby to revolve therewith, a series of hollow saddle pieces 25 secured to the drum and communicating therewith and supporting the screens at one end, each of said hollow saddle pieces having a central deflector to deflect into the screen material received from the drum 30 from either direction, and means to secure the screen to the hollow saddle piece.

8. In a grinding mill the combination of a grinding drum, a hollow saddle piece secured to the drum and communicating 35 therewith at each end, said saddle piece having a central deflecting surface, a tubular screen supported at one end by the saddle

piece and means to secure the tubular screen to the saddle piece.

9. In a grinding mill the combination of 40 a grinding drum, a hollow saddle piece secured to the drum and communicating therewith at each end, said saddle piece having a central deflecting surface, a tubular screen supported at one end by the saddle 45 piece, a cap piece to secure the screen to the saddle piece, and a bolt to secure the cap piece to the saddle piece.

10. In a grinding mill the combination of a grinding drum, a hollow saddle piece 50 secured to the drum and communicating therewith at one end, said saddle piece having a central deflecting surface, a tubular screen supported at one end by the saddle 55 piece, a ring to receive the end of the screen and to be received in the saddle piece with capacity for longitudinal movement, removable means to hold the ring in place in the saddle piece, and means at the other end of the screen to support the same on the drum, 60 such means comprising a hollow casting, a ring to receive the end of the screen and seated on the casting, and means to secure the ring to the casting.

11. In a grinding mill the combination 65 of a grinding drum, a tubular screen supported thereby to revolve therewith, a saddle piece and removable cap piece to support the screen at one end, and a hollow casting and removable ring to support the 70 screen at the other end.

This specification signed this 13th day of September A. D. 1924.

POVL T. LINDHARD.
